Primary Examiner — Elizabeth J Oswecki*(74) Attorney, Agent, or Firm* — Arthur Z. Bookstein**CLAIM**

The ornamental design for a money savings container, as shown and described.

DESCRIPTION

FIG. 1 is a perspective view of a money savings container showing my new design;

FIG. 2 is a front elevation view thereof;

FIG. 3 is a right side elevation view thereof;

FIG. 4 is a left side elevation view thereof;

FIG. 5 is a bottom view thereof; and,

FIG. 6 is a top view thereof.

All surfaces not shown form no part of the claimed design.
